United States Patent Office

Des. 198,069
Patented Apr. 21, 1964

198,069

CERVICAL COLLAR

Nicholas C. Connelly, Eaton Rapids, Mich., assignor to
S. H. Camp & Company, Jackson, Mich., a corporation
of Michigan

Filed Dec. 17, 1962, Ser. No. 72,883

Term of patent 14 years

(Cl. D83—1)

FIG. 1

FIG. 2

FIG. 3

FIG. 4

FIG. 1 is a front perspective view of a cervical collar, showing my new design,

FIG. 2 is a side elevation thereof, the opposite side being substantially the same as the side shown,

FIG. 3 is a rear elevation thereof, and

FIG. 4 is a front elevation thereof.

The dominant features of my design reside in the full line portion.

I claim:

The ornamental design for a cervical collar, as shown and described.
